UNITED STATES PATENT OFFICE

2,390,118

COATING MACHINE

John H. Murch, East Orange, N. J., assignor to
 American Can Company, New York, N. Y., a
 corporation of New Jersey

Application September 11, 1942, Serial No. 458,021

10 Claims. (Cl. 91—53)

This invention relates to coating machines and the like for applying a coating such as paraffin wax to the surface of fibre containers and has particular reference to removing excess coating material from the containers after the coating operation.

In the manufacture of coated fibre milk containers of the character disclosed in United States Patent 2,085,979, issued July 6, 1937, to J. M. Hothersall, the container is preferably immersed in a bath of molten paraffin wax so that the surfaces of the container are thoroughly covered. After such a coating operation according to established practices the container is placed in position to permit the excess wax to drain away.

It has been found that not all of the excess wax drains away from the container during this operation. A greater amount of wax than is actually required still remains on the surfaces of the container and this excess wax sometimes is unattractive in appearance and unpleasant to the touch. By removing all excess wax and leaving only that which is required, considerable wax may be saved for reuse in addition to improving the appearance, etc.

The instant invention contemplates overcoming these difficulties by removing all unnecessary applied coating material from the surfaces of the containers by the use of an air blast so that only the required minimum amount of the material will remain in place on the container.

An object therefore of the invention is the provision, in a machine for applying coating material to the surface of fibre containers, of devices which project a fluid decoating medium against the surfaces of newly coated containers to remove all excess coating material so that only a predetermined minimum film of the coating material will remain in place on the containers.

Another object is the provision of such devices wherein air is projected against the newly coated surfaces of the containers to remove all excess coating material so that an attractive and clean coated container will result.

Another object is the provision of devices of this character which will effect the removal of all excess coating material from containers while they are moving at high speed and in a continuous procession so that continuous high speed production may be had.

Numerous other objects and advantages of the invention will be apparent as it is better understood from the following description, which, taken in connection with the accompanying

drawings, discloses a preferred embodiment thereof.

Referring to the drawings:

Figure 1 is a top plan view of a portion of a coating machine embodying the instant invention, with parts broken away and shown in section and with containers shown in place in the machine;

Fig. 2 is an enlarged vertical section taken substantially along the line 2—2 in Fig. 1, with parts broken away and showing containers in place in the apparatus;

Fig. 3 is an enlarged sectional view of a portion of the apparatus and taken substantially along the line 3—3 in Fig. 1, with parts broken away;

Fig. 4 is a side elevation of the portion of the apparatus shown in Fig. 3, with parts broken away and shown in section;

Fig. 5 is a horizontal section taken substantially along the line 5—5 in Fig. 3, with parts broken away and containers in place in the apparatus;

Fig. 6 is an enlarged perspective detail of one of the air blast units, with parts broken away and shown in section;

Fig. 7 is a sectional view taken substantially along a plane indicated by the lines 7—7 in Fig. 6;

Fig. 8 is a horizontal section taken substantially along the line 8—8 in Fig. 7;

Fig. 9 is an enlarged side elevation of certain parts of the apparatus as viewed along a vertical plane indicated by the line 9—9 in Fig. 1, with parts broken away;

Fig. 10 is a sectional detail of parts shown at the lower right in Fig. 2, with the container and its adjacent parts shown in a different position; and

Fig. 11 is an enlarged schematic perspective view of the parts shown in Fig. 4, with parts broken away and shown in section.

As a preferred embodiment of the present invention the drawings illustrate principal parts of a coating and treating machine for applying a coating of paraffin wax or the like onto containers, as for example the fibre milk container disclosed in the Hothersall patent above mentioned. The container is indicated by the letter 'b' in the drawings. The container referred to preferably is square in cross section although the invention is equally well adapted to cylindrical containers. Such a square container is formed in its top end with a dispensing opening 'c' which is adapted to be closed with a friction plug closure element 'd' hingedly secured to the container top.

In the machine illustrated in the drawings, the

empty containers *b* are fed by a continuously moving conveyor *A* through a coating chamber *B* in which the containers receive a coating of paraffin wax. The chamber *B* is heated preferably to facilitate application of the wax in a molten condition.

The freshly coated containers are received from the coating conveyor *A* in a continuously rotating transfer mechanism *C* and are carried through a curved path of travel of approximately one hundred eighty degrees. During this curved travel of a container, its exterior surfaces are subjected to an air blast. This air blast removes all excess wax and leaves the containers with a clean, attractive appearance and with a minimum film of the wax in place to serve as a protective coating.

After such a wax removing operation the cleaned container is deposited on a constantly moving cooling conveyor *D*. This conveyor extends through a cooling chamber *E* in which the wax coating remaining on the surfaces of the container becomes chilled and hardened. The conveyor carries the chilled containers to any suitable place of deposit.

The coating conveyor *A* extends longitudinally of the machine in a horizontal position and is enclosed in a casing *H* which constitutes a portion of the main frame of the machine. It is this casing that encloses the coating chamber *B*. The conveyor comprises a plurality of V-shaped buckets *I* (Figs. 1 and 2), which are semi-circular in cross-section and which are connected together by pairs of links to form an endless chain. This conveyor travels over and is driven by chain sprockets located at opposite ends of the machine.

The coating conveyor *A* is guided in a straight line path of travel by upper and lower guide tracks *J* formed in brackets *K* bolted to cross beams *L* of the main frame. The containers propelled by the conveyor fit into the V-shaped buckets *I* and are retained in place by a pair of spaced and parallel guide rails *M*.

A closure guide rail *N* is disposed adjacent the rails *M* for holding the closure element *d* of the container in an open position, as best shown in Fig. 1. It is while the containers are moving along with this conveyor that the molten wax coating is applied. This coating may be applied by immersion or spraying or in any other suitable manner. Coating by immersion and using the same type of conveyor *A* is disclosed in the James H. Gordon, Jr., Patent 2,298,289 issued October 13, 1942, on Coating machine. The conveyor advances the freshly coated containers in an upright position toward the transfer mechanism *C*.

The transfer mechanism *C* is disposed adjacent the coating conveyor *A* and is enclosed in a vertical multiple part housing *P* (Figs. 1 and 2). A portion of this housing is formed integral with and extends up from the coating chamber casing *H*.

Within the housing, the transfer mechanism includes a rotatable turret body *Q* (Figs. 2, 3, 5 and 11) having a plurality of flat faces *R* on which are secured a plurality of pairs of vertically spaced upper and lower triangular blocks *S*, *T*. These pairs of blocks are equally spaced around the outer periphery of the turret body. Taken collectively the peripherally spaced blocks set off between them a plurality of V-shaped upper turret pockets *U* and lower pockets *V* which extend around the turret body for receiving the

containers *b*. Vertical ribs *W* on the sides of the blocks engage against the containers to reduce contact with the outside surface of the containers.

5 The turret body *Q* is mounted on a vertical shaft *X* which is journaled in upper and lower bearings *Y*, *Z*. The upper bearing *Y* is formed in a cover part *A* of the housing *P* while the lower bearing *Z* is formed in a member *B* of the main frame. The shaft is continuously rotated in time with the other parts of the machine by a spur gear *C* which is keyed to the upper end of the shaft.

Hence as the shaft *X* rotates the turret body *Q*, the lower set of pockets *U* between the turret blocks *S* pick up the containers from the coating conveyor *A* as the pockets come adjacent the conveyor, and propel them along the curved path of travel hereinbefore mentioned. A curved guide rail *D* (Fig. 1) disposed adjacent this path of travel retains the containers in place in their turret pockets.

10 During this travel of the containers with the transfer turret, excess wax on the containers is prevented from adhering to the turret parts by maintaining the latter in a heated condition. For this purpose the turret body is made hollow and steam, hot water, or any other suitable fluid heating medium is circulated therethrough to heat the turret parts to the proper temperature.

15 Circulation of the heating medium through the turret body *Q* is effected by way of an inlet bore *E* (Figs. 1 and 2) which extends down through the middle of the upper portion of the vertical shaft *X*. The upper end of the bore communicates with an inlet tube *F* which is suitably secured as by a slip joint in the upper end of the shaft. The tube leads from any suitable supply of the heating medium.

20 The lower end of the inlet bore *E* terminates adjacent the upper end of the turret body *Q* and communicates with the interior of the turret body by way of a port *G*. This port extends through the inner wall of the turret body and through the shaft *X*. Near the lower end of the turret body an outlet port *H* extends from the body interior to an outlet bore *I* formed in the middle of the lower portion of the shaft *X*. This outlet bore *I* extends to the lower end of the shaft where it communicates with a discharge tube *J*. The discharge tube is suitably secured as by a slip or universal joint in the lower end of the shaft and leads to any suitable place of deposit for the heating medium. It is this construction, that permits of the circulation of the heating medium through the turret body.

25 Immediately after a lower pocket *U* of the transfer turret has picked up a container *b* from the coating conveyor *A*, the container begins an upward travel as well as the curved travel. For the first 90 degrees of curved travel, i. e., about one-half its full curved travel, the container moves up into the upper pockets *V* between the upper blocks *S*. This upward travel is effected by a vertically disposed lift bar *K* (Figs. 1, 2 and 10).

30 There are a plurality of lift bars *K*, one for each set of upper and lower pockets *V*, *U* and they are located adjacent the inner ends of the pockets. These lift bars slide in vertical grooves *L* formed in the outer side wall of the turret body *Q*. The lower end of each lift bar is formed with an outwardly extending foot *M* which projects under the container.

35 The upper ends of the lift bars *K* project up

through slideways 62 formed in a disc 63 (see also Fig. 11) having a depending flange hub 64 which is bolted to the top of the turret body 26. The disc thus rotates with the turret body. The upper ends of the lift bars 57 are formed with rack teeth 66 which engage with lifting gears 67 (see also Fig. 9) of lifting devices 68. There is one of these lifting devices for each lift bar 57.

The lifting gears 67 of the lifting devices 68 are mounted on the inner ends of short horizontal shafts 71 which are carried in bearing brackets 72 bolted to the top of the disc 63. There is one bracket for each lifting device. The outer ends of the shafts 71 carry pinions 73 which mesh with segment gears 74 mounted on short shafts 75 carried in the bearing brackets. The shafts 75 also carry cam arms 76 having at their outer ends, cam rollers 77 which operate between two spaced and parallel cam edges 78, 79 (Fig. 2) of a pair of upper and lower stationary ring cams 81, 82. These ring cams are bolted in place within the housing 25. Hence as the disc 63 rotates with the turret body 26, the cam rollers 77 of the lifting devices 68 traverse the cam edges 78, 79 and thus rock the cam arms 76. Rocking of these arms rotates the segment gears 74, the pinions 73, and the rack gears 67 and thus raises and lowers the lift bars 57 at the proper time. Raising of a lift bar brings its foot 59 into supporting engagement with the bottom of its associated container and thus lifts the container vertically while it is moving around its curved path of travel.

As soon as a container is engaged by a lifter foot 59 it is locked in place against lateral displacement from its lift bar. This is brought about by a locking finger 85 (Figs. 2 and 10) which is mounted on a pivot pin 86 secured in an insert block 87 carried in the lift bar. There is one of these insert blocks and its locking finger for each lift bar.

The locking finger 85 extends outwardly over the top of a container adjacent a lift bar and is formed with a notch 91 which is in alignment with the end seam of the container. The inner end of the finger is formed with a tail 92 which extends through a slot in the insert block 87 and engages against the outer surface of the turret body 26. A compression spring 93 retained in a bore in the insert block presses against the locking finger and holds its tail in engagement with the turret body.

The engagement of the tail 92 of the locking finger 85 against the outer surface of the turret body 26 retains the finger in a raised position over a container as best shown in Fig. 2. This position of the finger permits of the ready insertion of a container into its turret pocket 32. However, as soon as the seated container begins to rise with its lift bar 57, the tail of the locking finger rides into a groove 94 formed in the turret body adjacent the lift bar and this allows the spring 93 to press the finger down onto the top of the container, as best shown in Fig. 10. There is one of these grooves 94 adjacent each lift bar. In this depressed position of the finger, its notch 91 engages over the end seam of the container and thus locks the latter in place against displacement from the lift bar while it is being elevated into the upper pockets 31 between the upper turret blocks 28.

During this upward travel of the container, the excess wax is blown off its top, side, and bottom surfaces by a blast of air which is directed against these surfaces. This blast of air issues from inner

and outer air heads 101, 102 which rotate with the turret body 26 and the disc 63.

The inner air heads 101 are triangular in shape to correspond with the upper turret blocks 28. Each head preferably is made in three pieces, a top member 104 (Figs. 3, 6 and 7), an intermediate member 105 and a bottom member 106. These parts are superimposed one upon the other and are all secured by a bolt 107 to the bottoms of the upper turret blocks 28.

The sides of the bottom member 106 adjacent the upper turret pockets 31 are beveled inwardly and are formed with short ribs 111 for engaging and for guiding a container *b* into an upper pocket 31 as the container rises. The top edges of these sides of the member are also beveled to provide a pair of narrow nozzle slots 112 between the bottom member 106 and the next above intermediate member 105. It is from these slots that the air issues and impinges against the adjacent sides of the container while the latter moves up into the upper pockets 31.

Air under pressure is supplied to the slots 112 by way of passageways 114, 115 formed in the bottom of the intermediate member 105 along its sides, adjacent the slots 112 in the bottom member 106. These passageways communicate by way of ports 116, 117 in the intermediate member with openings 118, 119 formed in the adjacent superimposed top member 104.

The openings 118, 119 in the top member 104 of the air heads 101 are in communication with the lower ends of a pair of pipes 125, 126 which extend up through the turret blocks 28. The upper ends of these pipes are connected by flexible tubes 127, 128 to pipe nipples 129, 130 which are secured into the bottom of the disc 63. The nipples communicate with horizontal radial bores 135 (see also Fig. 11) which are formed in the disc.

It should be noticed in this connection that each horizontal bore 135 is in communication with the tube 128 for one head 101 and with the tube 127 for the next adjacent head 101. This is best illustrated in Figs. 4 and 11. Such a construction permits of greater speed in removing the excess wax from the containers, as will be hereinafter explained in more detail.

The inner ends of the horizontal bores 135 communicate with separate vertical bores 137 which are formed in an enlarged hub 138 on the disc 63. The upper ends of these vertical bores register with corresponding holes 139 formed in a hardened plate 141 secured to the top of the disc hub. When the machine is in operation the hardened plate 141 on the disc hub 138 rotates against a stationary plate 143. This stationary plate is formed with an elongated slot 145 into which the holes 139 of the plate come into register as the plate rotates. The slot is just long enough to have two holes 139 in register with it at the same time.

The stationary plate 143 is secured to the bottom of a stationary cover member 147 having a long sleeve 148 which extends up around the vertical shaft 36. The upper end of the sleeve fits inside of a depending skirt 149 of the shaft bearing 37 and is locked in place against rotation by a tongue and groove connection 151 formed between the skirt and the sleeve. This connection holds the cover member and its plate 143 stationary. A compression spring 152 disposed around the sleeve and interposed between the shaft bearing 37 and the cover member 147 holds 75 the stationary plate tightly against the rotating

plate 141 so that leakage of air between the plates is prevented.

The cover member 147 is formed with an annular groove 155 which is in communication with the elongated slot 145. Groove 155 is also in communication with a feed pipe 156 which is threadedly secured in the cover member. This pipe leads from a suitable source of supply of compressed air. It is this air that issues from the nozzle slots 112 in the inner air heads 101.

The outer air heads 102 are formed in quadrants 161 (Fig. 5) of a head ring 162 which is disposed adjacent the inner heads 101 and which surrounds the transfer turret. This head ring and a cooperating bottom ring 163 (see also Figs. 2 and 3) rotate with the transfer turret. For this purpose the rings 162, 163 are secured by bolts 164 to support arms 165 which depend from the disc 63.

The inner edges of the head ring quadrants 161 are serrated to provide V-shaped pockets 167 which form a major portion of the outer heads 102. These pockets are located opposite the pockets 31 of the inner heads 101 and taken together form rectangular clearance openings between the turret and the surrounding head ring 162 for the passage of the rising containers. In this manner a rising container is substantially surrounded by the combined inner and outer air heads 101, 102 as it passes up into the upper turret pockets 31.

Adjacent the pocket edges of the head ring 162, the bottom of each ring quadrant is formed with a groove 171. The inner ends of these grooves terminate adjacent the inner peaks of the serrations and are disconnected from the grooves of the adjacent heads. The outer ends of the grooves of each head are connected so that there will be a continuous passageway along the pocket of each head 102. Each set of grooves is connected by a port 172 in the head ring and a connecting passageway 173 in the support arms 165, with a port 174 in the disc 63 which leads from the horizontal bores 135 in the disc.

Thus compressed air from the main source of supply as it enters the horizontal bores 135 for distribution to the inner heads 101, also flows by way of the passageways 173 in the support arms to the grooves 171 of the outer heads 102. This air issues from the heads 102 by way of nozzle slots 176 (Figs. 2 and 3) which are formed between the inner edges of the head ring 162 and its cooperating bottom plate 163. For this purpose the inner top edge of the bottom plate is beveled outwardly to form the space which constitutes the nozzle slots. The inner lower edge of this plate is beveled inwardly and is formed with ribs 177 for guiding a container up through the rectangular openings formed by the cooperating inner and outer pockets 31, 167.

Thus as a container *b* rises up by elevation of a lift bar 57, the hole 139 in the rotating plate 141 connecting with the air pipes, passageways and ports leading into the inner and outer heads 101, 102 adjacent the container, comes into register with the elongated slot 145 in the stationary plate 143 and thus permits compressed air from the groove 155 of the cover member 147 to flow into the air heads and to issue from their nozzle slots 112, 176. The hole 139 remains in register with the elongated slot 145 until the container nearly reaches the top of its up-travel. The remainder of the up-travel is covered by the next following hole 139 and by the pipe connection 75

125, 127 of the next following head 101, as hereinbefore mentioned.

During this blast of air from the head nozzle slots 112, 176 the container moves up past the slots, through the rectangular opening formed by the head pockets, and into the upper turret pocket 31. While the container is thus moving up the blast of air impinges first against and across the top of the container and blows off any excess wax adhering to this surface. As the container ascends the air blast next impinges against the sides of the container and thus wipes down any excess wax which may be on these surfaces. This wiping action flows the excess wax downwardly along the sides of the container until it reaches the bottom. As the bottom of the container passes the nozzle slots, the wax gathered at this portion of the container is blown off and falls to any suitable place of deposit from which it may be collected for reuse.

In order to prevent the blown off wax from solidifying onto the parts of the outer air heads 102, the heads are heated by a suitable heating medium such as steam, hot oil, hot water or the like fluid. This fluid is circulated through a jacket 181 (Fig. 2) which surrounds the head parts and which is bolted to the heating chamber casing 11. The heating medium is circulated through this jacket by way of an inlet pipe 182 which leads from a suitable source of the heating medium and by way of an outlet 183 formed as a part of the jacket.

The lifting of the container for the excess wax removing operation is effected as the transfer turret travels through slightly less than 90 degrees, as hereinbefore mentioned. As soon as the container reaches the peak of its up-travel, it immediately begins to descend to its original level. This descent of the container is brought about by the same elements that elevated it and in substantially the same angle of travel of the transfer turret. However, during this down-travel no air blast is applied to the container. The port 139 which admits air into its heads 101, 102 passes beyond the elongated slot 145 at the peak of the up-travel of the container. Hence the air communicating with the heads 101, 102 is cut off for this down-travel of the container.

On the down-travel, the rotating transfer turret brings the container into reach of the cooling conveyor D. This conveyor preferably includes a horizontal endless chain 185 (Figs. 1 and 2) which operates over a sprocket 186 mounted on a vertical shaft 187 journaled in suitable bearings 55 formed in the main frame of the machine. The shaft is rotated in any suitable manner in time with the other moving parts of the machine.

The chain 185 carries a plurality of spaced carriages 191 which are guided by upper and lower rollers 192, 193. The upper rollers are guided in grooved tracks 194 suitably held in fixed position over the path of the rollers. The lower rollers 193 are flanged and ride on track rails 195 mounted in stationary position on the frame of the machine. Carriages 191 receive the containers from the transfer turret when the latter reach their down stroke in the turret and after they have been released by the locking fingers 85, hereinbefore mentioned. A container received in a carriage of the conveyor D is propelled through the cooling chamber E where the desired film of wax remaining on the container, after the excess has been removed, is cooled and hardened. The conveyor then carries the cooled container to any suitable place of deposit.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for coating fibre containers with liquid paraffin wax and the like, the combination of a plurality of head members arranged in positions for completely surrounding a freshly coated container in closely nested relation, such arrangement forming a clearance opening through which the container is adapted to be passed while in a vertical position, said head members having nozzle slots in their inner faces through which air under pressure is ejected against the container to remove excess coating material therefrom, and means disposed adjacent said head members for elevating the container through the opening between the head members so that the air under pressure impinges against all exterior surfaces of the container.

2. In a machine for coating fibre containers with liquid paraffin wax and the like, the combination of a plurality of head members arranged in positions for completely surrounding a freshly coated container, such arrangement forming a clearance opening through which the container is adapted to be passed, said head members having nozzle slots in their inner faces through which air under pressure is ejected against the container to remove excess coating material therefrom, means for supplying air under pressure to said head members, means disposed adjacent said members for elevating the container through the opening between the said members into the path of the ejected air and thence for returning the container to its original position, and valve means for cutting off the supply of air from said head members during the return of the container to its original position.

3. In a machine for coating fibre containers with liquid paraffin wax and the like, the combination of a rotatable turret member having a pocket for the reception of a freshly coated container, head means carried by said turret member and disposed above said container pockets so as to completely surround a container, thereby setting off an enclosed clearance opening through which the container is adapted to be passed, said head means being apertured for the ejection of a blast of air under pressure into said opening, means for supplying air to said head means, and elevating means carried in said turret member for passing the container up through the said air blast whereby the excess coating material is wiped off the outer surfaces of the container while it is moving with said turret member.

4. In a machine for coating fibre containers with liquid paraffin wax and the like, the combination of a rotatable turret member having a plurality of spaced pockets for the reception of freshly coated containers, head means carried by said turret member and disposed above each of said container pockets so as to completely surround a container, thereby setting off enclosed clearance openings through which containers are adapted to be passed, said head means of each container pocket having means for ejecting a blast of air under pressure into its clearance opening, means for supplying air to

said head means, and means carried in said turret member adjacent each pocket for elevating a container through the air blast being ejected into its head opening for wiping the excess coating material from the outer surface of the container while it is moving with said turret member.

5. In a machine for coating fibre containers with liquid paraffin wax and the like, the combination of a plurality of head members arranged in positions for completely surrounding a freshly coated container, such arrangement forming a clearance opening through which the container is adapted to be passed, means for supplying air under pressure to said head members and into said clearance opening as an air blast, means disposed adjacent said members for elevating the container through the said clearance opening into the path of said air blast, and a locking finger carried by said elevating means and movable into engagement with the container to lock the same in place on said elevating means during movement of the latter so that excess coating material may be effectually removed from the container.

6. In a machine for coating fibre containers with liquid paraffin wax and the like, the combination of a plurality of head members arranged in positions for completely surrounding a freshly coated container, such arrangement forming a clearance opening through which the container is designed to be elevated, said head members having nozzle slots in their inner faces through which air under pressure is ejected against the container to remove excess coating material therefrom, means for elevating the container through the opening between the head members into the path of the ejected air, and means for heating said heads to prevent the removed excess coating material from collecting thereon.

7. In a machine for coating fibre containers with liquid paraffin wax and the like, the combination of a rotatable turret member having a plurality of pockets for the reception of freshly coated containers, a plurality of head members on said turret member arranged so that two adjacent head members partially surround a container, thereby setting off inner pockets between them and disposed above and in vertical alignment with said turret pockets, said head members having nozzle slots for the ejection of an air blast into and across said head pockets, means surrounding and rotating with said turret member for setting off outer pockets which cooperate with said inner pockets to form a plurality of enclosures each of which is adapted to completely surround a container, said surrounding means having a plurality of nozzle slots for the ejection of an air blast into and across said outer pockets, means for supplying air under pressure to said surrounding means, and means for passing a freshly coated container through said inner and outer pockets while the container is carried in said turret member so that the air blast issuing from said nozzle slots wipes off excess coating material from the top, side, and bottom surfaces of the moving container.

8. In a machine for coating fibre containers with liquid paraffin wax and the like, the combination of a rotatable turret member having a pocket for the reception of a freshly coated container, a conveyor for depositing the container into the pocket of said turret member, head means disposed above said container pocket and arranged to completely surround a container,

thereby setting off an enclosed clearance opening through which the container is adapted to be passed, said head means having a plurality of ports communicating with said opening, means for ejecting a blast of air under pressure through said ports into said opening, means carried in said turret member for elevating the container through the path of the air blast within said head opening for wiping the excess coating material from the outer surfaces of the container while it is moving with said turret member, and a discharge conveyor for receiving the wiped off container from the turret member and for carrying it to a suitable place of deposit.

9. In a machine for coating fibre containers with liquid paraffin wax and the like, the combination of a rotatable turret member having a pocket for the reception of a freshly coated container, means for rotating said turret member, head means disposed above said container pocket and arranged to completely surround a container, thereby setting off an enclosed clearance opening through which the container is adapted to be passed, said head means having a plurality of ports communicating with said opening, means for projecting a blast of air under pressure through

5 said ports into said opening, means carried in said turret member for elevating the container into the path of said air blast, and means for actuating said elevating means to carry the container through the air blast to wipe off excess coating material from its outer surfaces and for lowering the wiped container to remove it from said clearance opening, the raising and lowering of the container taking place during the rotation of said 10 turret member.

10. In a machine for coating fibre containers with liquid paraffin wax and the like, the combination of a plurality of head members arranged in positions for completely surrounding a freshly 15 coated container, such arrangement forming a clearance opening through which the container is adapted to be passed, said head members having nozzle slots in their inner faces through which air under pressure is ejected against the container to 20 remove excess coating material therefrom, and means disposed adjacent said head members for moving the container through the opening between the head members so that air under pressure impinges against all exterior surfaces of the 25 container.
